UNITED STATES PATENT OFFICE.

ALEXANDER BERNHARD DRÄGER, OF LUBECK, GERMANY.

RESPIRATORY APPARATUS.

Application filed June 9, 1921. Serial No. 476,235.

To all whom it may concern:

Be it known that I, ALEXANDER BERNHARD DRÄGER, a citizen of Germany, residing at Lubeck, Germany, have invented certain new and useful Improvements in Respiratory Apparatus, of which the following is a specification.

This invention relates to that type of respiratory apparatus which include a breathing bag and a reservoir adapted to be heated for gasifying liquefied gas, such as liquid air, liquid oxygen or a mixture of liquid oxygen and nitrogen, to support respiration and in which the vaporization of the gas is accomplished by the heat of the surrounding external atmosphere in contradistinction to that type of apparatus in which the heat of the exhaled air is utilized for the same purpose. In the known appliances of the type to which the present invention has reference the vaporization is effected by the direct heating effect of the surrounding atmosphere or by affording the external atmosphere an opportunity to flow through a heating pipe which surrounds or passes through the reservoir containing the liquid, in order to give up its heat to this latter. The extent of the vaporization in the latter type of apparatus referred to depends upon the volume and the velocity of the external air which flows through the heating pipe and which is unequally warm owing to the natural equilization of weight. In order to enable the vaporization of the liquid gas provided to support respiration in such apparatus to be determined and controlled, the heating pipe is caused to communicate with the outer air by adjustable openings in the form of stop cocks or the like. By opening the heating pipe more or less, more or less of the outer air is allowed to flow through so that the volume of the liquefied gas which is to be vaporized to support respiration can be suitably regulated by suitable adjustment of the cocks on the heating pipe to correspond to the respiratory requirements of the moment. The increased or diminished requirements of respiration of the wearer of the apparatus can be therefore accommodated only by a strict and continuous control of the heating pipe and of the volume of the outer air flowing through it. Such an adjustable vaporization of the liquid gas for supporting respiration by the heat of the outer air is

however troublesome and inconvenient and not always reliable.

The object of the present invention is to provide an apparatus in which these disadvantages and objections are overcome and in which the vaporization of the liquid gas for supporting respiration is automatically effected and controlled by the operation of breathing itself; that is to say the suction and force movements of the breathing bag belonging to the apparatus (i. e., the deflation and inflation thereof) are used to bring the required outer air into contact with the reservoir containing the liquid and to drive it through its heating pipe, so that the supply of air and consequently the extent of the vaporization depends upon the depth and frequency of the periods of respiration and is automatically regulated at all times according to the respiratory requirements of the wearer of the apparatus.

The course of the outer air controlled by the breathing bag can in this apparatus be so determined, by the aid of suction and force valves which conveniently communicate with the heating pipe, that the outer air is compelled to always flow through the heating pipe in one direction. With this arrangement the breathing bag is only brought into contact with the comparatively warm outer air and not with the air which is cooled down by the reservoir for the liquid, and therefore does not become hardened or otherwise damaged.

The heating up of that portion of the outer air which serves as the heating agent may also be effected by making use of the heat produced by the respiration particularly through the carbonic acid absorption in the air purifying charge of the cartridge or absorber connected with the apparatus. For this purpose the structure of the apparatus is so arranged that the charge gives up its radiant heat to the outer air which is set in motion by the breathing bag and acts as heating air.

In the accompanying drawing:

Figure 1 is an elevation, partly in section of a constructional example of a respiratory apparatus embodying this invention.

Figure 2 is a similar view showing a modified constructional form.

Figures 3 and 4 are similar views of two further constructional forms of the respiratory apparatus.

The liquefied gas, for example, liquid oxygen for supporting respiration is contained in a reservoir *a* (see Figure 1) of a kind suitable for the purpose and filled with a convenient insulating composition *a'* such as asbestos or the like. This reservoir is located in the well known way in an external receptacle *b* which protects it from the effects of the outer air. In the receptacle *b* is also placed the breathing bag *c* of the respiratory apparatus which may be of any usual form and is connected in the well known way with an air purifying cartridge or absorber *d*, a valve chest *e* provided with an inhalation valve *e'* and an exhalation valve *e''* and a breathing pipe *f* leading to the part of the apparatus, acting as intermediary to the breathing organs, that is to say, to the mouthpiece *r* (Figure 1) or the mask *s* (Figure 2). From the reservoir *a*, a pipe *g* leads to the valve chest *e*, in order to convey the vaporized liquid gas, for supporting respiration into the air passages of the apparatus.

When the wearer of the apparatus is inhaling, the breathing bag *c* collapses from the position shown by dotted lines in Figure 1, into approximately the position shown by full lines therein and thereby exerts a suction action in the outer receptacle *b* which draws external air in through the apertured boss *h* located in the wall of the receptacle *b*. When the wearer exhales, the breathing bag *c* again becomes inflated and expels the air previously drawn into the receptacle *b* out through the apertured boss *h*. This operation is of course repeated. The suction and pressure movements of the breathing bag in the receptacle *b* cause the outer air which is drawn in and expelled again to flow through the intermediate spaces existing between the reservoir *a* for the liquid and the receptacle *b* and constituting heating passages. The air may also be caused to pass through a special heating pipe *i* which traverses the reservoir *a* as shown in the drawing, said air being admitted in one direction and expelled in another and giving up its heat to the reservoir *a* and its contents as it passes through the apparatus. The liquid vaporized thereby passes through the pipe *g* into the respiratory apparatus. The stronger, that is to say, the deeper and more frequent the breathing of the wearer of the apparatus, the more the outer air is moved to and fro in the receptacle *b* and the more gas to support respiration will be generated from the liquid in the reservoir *a*. The supply of gas to the apparatus for supporting respiration is therefore automatically regulated by the act of breathing itself.

In many cases it will be found convenient to arrange the reservoir *a* for the liquid and the breathing bag *c* each in a separate enclosing receptacle *b'* and *b''* respectively

(see Fig. 3) and to connect the receptacles by a passage *h* or the like.

If it is desired to prevent the breathing bag from becoming hardened by contact with the air which has been cooled down by contact with the reservoir *a*, this may be effected by compelling the outer air to pass in one direction only by means of non-return valves around or through the reservoir *a*. For this purpose the enclosing receptacle *b* (see Figures 2 and 4), and *b'* (Figure 3) is provided with an inlet socket *m* which latter is furnished with a suction valve *n* arranged to open automatically when the wearer inhales (deflation of the breathing bag) while the socket *h* which now merely serves as an outlet is fitted with a pressure valve *o* (see Figures 2 and 4) which opens automatically when the wearer exhales (inflation of breathing bag). Figure 3 shows that such a pressure valve *o* instead of being arranged in the outlet socket *h* of the receptacle *b'* which surrounds the reservoir *a* for the liquid may also be arranged in the passage or connecting branch *h*.

In the constructional examples shown in Figures 2 and 4 during the suction period of the breathing bag, external air is drawn into the receptacle *b* through the automatically opening valve *n*, whilst the valve *o* remains closed. The outer air thus drawn into the receptacle *b* as the breathing bag is deflated is expelled again by the next subsequent inflation of the breathing bag, through the valve *o* which opens automatically, whilst the valve *n* remains closed. During the expelling movement the air flows around the reservoir *a* for the liquid or through the heating pipe *i* thereof respectively.

In the constructional example shown in Figure 3 the outer air which is drawn into the receptacle *b'* by the suction stroke of the breathing bag, is forced over by the next pressure stroke through the pressure valve *o* into the reservoir *b'* and heating pipe *i* respectively, where it temporarily remains; the transferred air does not pass out through the unobstructed socket *h* into the open air, until the next pressure stroke of the breathing bag takes place when it is expelled by the new charge of outer air drawn in the action of the breathing bag and so on. In the apparatus shown in Figures 2 to 4 the breathing bag therefore acts similarly to a single acting pumping apparatus which delivers in one direction only; in other words the outer air is drawn in at one stroke and driven out on the next stroke around the reservoir for the liquid or through the heating pipe thereof. This is done in such a way that the flow always takes place in the same direction and cooled air does not come into contact with the breathing bag. In the apparatus shown

in Figure 1 the breathing bag, on the contrary, acts in the same manner as the piston of a syringe in that it expels the air drawn in through the socket *h* into the receptacle *b* 5 through the same opening again; the heating air thus has a to and fro movement imparted to it around or through the reservoir for the liquid, the air cooled down on the inward movement by contact with the reservoir *a* passing over the breathing bag which is avoided in the apparatus according to Figures 2 to 4.

Figure 4 shows the manner in which the heating of the chemical charge of the absorber *d* by the exhaled air or by the heat developed by the absorption of the carbonic acid respectively can be utilized to warm up the outer air which is to serve for the heating of the reservoir containing the liquid. 10 This is effected by locating the absorber *d* simply in the receptacle *b* (or *b*² in Figure 2) or by arranging it in sufficiently close proximity to the receptacle, so that the heat developed by the charge of the absorber and 15 radiating from it warms up the air in the receptacle.

In order to avoid over-inflation of the breathing bag with gas to support respiration resulting from excessive vaporization, 20 it is advisable to provide the breathing bag with an outlet fitted with a non-return valve through which the amount of gas in excess of the requirements can escape. An outlet of this kind provided with a non-return 25 valve *p* is shown in Figure 1.

I claim:

1. In a respiratory apparatus of the class described the combination of a reservoir containing liquefied breathing gas to be heated and vaporized by external air to support respiration, containing means enclosing the said reservoir as an air heating jacket and being in communication with the atmosphere, and a breathing bag arranged within the said containing means 40 to automatically regulate, according to its pulsations, the external air supply to the said heating jacket.

2. In a respiratory apparatus of the class described the combination of a reservoir 50 containing liquefied breathing gas, a breathing bag, and containing means enclosing the reservoir and the breathing bag and being provided with an air inlet furnished with an inhalation valve, and with an air passage 55 provided with an exhalation valve whereby the flow of air through the apparatus is always in the same direction.

3. In a respiratory apparatus of the class described the combination of a reservoir 60 containing liquefied breathing gas, a breathing bag, a receptacle containing the reservoir and the breathing bag and being provided with means whereby a supply of external air is passed to and from the said receptacle, and an air purifying cartridge for the exhaled air located in the receptacle in 65 close proximity to the breathing bag.

ALEXANDER BERNHARD DRÄGER.
